UNITED STATES PATENT OFFICE.

KARL KEMPNY, OF CLEVELAND, OHIO.

MOVABLE SHIELD.

1,234,174.

Specification of Letters Patent. Patented July 24, 1917.

Application filed November 20, 1916. Serial No. 132,320.

To all whom it may concern:

Be it known that KARL KEMPNY, subject of the Emperor of Austria, residing at Cleveland, in the county of Cuyahoga and

5 State of Ohio, has invented certain new and useful Improvements in Movable Shields, of which the following is a specification.

This invention relates to movable shields for protecting troops in battle and clearing 10 away obstructions in front of troops when moving forward.

One object of the invention is to provide an improved general construction of devices of this character.

15 A second object of the invention is to provide a device of this character with an improved means for crushing down and raising over the shield any obstructions which may be met in its forward progress.

20 A third object of the invention is to provide a movable shield of this character having an improved form of bullet catcher and deflector.

A fourth object of the invention is the 25 provision of an improved device of this character having special means for the destruction of barbed wire entanglements.

With the above and other objects in view, as will be hereinafter apparent the invention 30 consists in general of certain novel details of construction and combinations of parts hereinafter fully described, illustrated in the accompanying drawings, and specifically claimed.

35 In the accompanying drawings, like characters of reference indicate like parts in the several views, and:

Figure 1 is a side elevation of a movable shield constructed in accordance with this 40 invention.

Fig. 2 is a rear elevation thereof.

Fig. 3 is a plan view of the front part thereof.

Fig. 4 is a section on the line 4-4 of 45 Fig. 1.

Fig. 5 is a section on the line 5-5 of Fig. 3.

Fig. 6 is a plan view of a portion of the rear end of the device showing one of the 50 steering wheels and adjacent parts.

Fig. 7 is a section on the line 7-7 of Fig. 4.

Fig. 8 is an enlarged detail section similar to Fig. 7 but showing the manner of bolting the bullet deflector to the rear wall, of the 55 device.

In the embodiment of the invention herein illustrated it will be seen that the shield comprises a front wall 10, side walls 11, rear walls 12 and top 13. The general plan 60 of the shield thus formed is rectangular and at the front there is provided an axle 14 whereon are mounted wheels 15 which may be driven, if desired, by means of a motor 16 located within the shield and connected to 65 the driving wheels by a chain 17. In order to stiffen the sides of the device angle iron braces 18 are provided and it will be seen from Fig. 1 that these braces are so arranged as to deflect a bullet striking them 70 either upward or downward according to which brace is struck.

At the rear end of the device there is provided an axle 19 to which are pivoted the steering knuckles 20 carrying the steering 75 wheels 21. These steering knuckles are connected by rods 22 with a lever 23 pivoted as at 24 and provided with a grooved semi-circle 25. At a suitable height to be grasped by a man walking behind the device there is 80 provided a steering handle 26 fixed on a shaft 27 journaled in the rear walls 12 and provided with a grooved pulley 28. Around the pulley 28 and semi-circular member 25 extends a cable 29 so that movement of the 85 steering handle swings the lever 23 and in turn operates the steering wheels 21.

In order to remove obstructions from in front of the device there is provided a pair of forwardly extending arms 30 to the front 90 end of which are connected the lower ends of arcuate side frames 31 the upper and rear ends of which are connected to the sides 11 as at 32. In the lower ends of these side frames is journaled a shaft 33 whereon is a sprocket 34 connected by a chain 35 with a sprocket 36 on the axle 14. On this shaft 33 is a steel drum 37 having periphery projections 38. This drum is so positioned as to be slightly above the ground and it 100 will be observed that it rotates in the same direction as the wheels 15 so that any object against which the drum engages will be rolled down by the engagement of the pro-

jections 38 and crushed beneath the drum. On the members 31 are also provided stub shafts 39 carrying sprockets 40 which are connected to sprockets 41 by chains 42, the sprockets 41 being fixed on the shaft 33. 5 Journaled about centrally of the side frames 31 is a shaft 43 whereon is fixed a gear 44 meshing with a gear 45 on the stub shaft 39 at each side of the machine. On the shaft 10 43 there is also provided a sprocket 46 which is connected by a chain 47 with a sprocket 48 fixed on a shaft 49 journaled in the side frames. On each of the shafts 43 and 49 are mounted steel drums 50 having projecting 15 fingers 51. The top or roof 13 is curved upward from front to rear and from the sides to the center so as to provide a sharp ridge 52.

Now when the device runs against any 20 obstruction such as a barbed wire entanglement part of the entanglement will be forced down underneath the cylinder 37 while the rest of the entanglement will be picked up by the fingers 51 and carried up 25 onto the top or roof 13. By reason of the peculiar formation of this top or roof the wire will either be torn up bodily from its stakes or will be stressed so that it will break and leave a clear passage for the soldiers 30 behind the shield.

Under ordinary circumstances any bullets which may strike the front of the shield will be deflected by the revolving cylinders but should any bullet strike the front wall with 35 sufficient force to penetrate the same provision is made on the rear wall to deflect such a bullet in a way that will absorb the shock of its impact and prevent its penetrating the rear wall. To effect this there is provided 40 on the rear wall a series of reversely curved plates 53 which extend transversely of the rear wall and are secured thereto by countersunk bolts 54. Moreover, each of these plates has its lower edge bent around the 45 upper edge of the next plate below as shown at 55 so that there is no opportunity for a bullet to strike in a crack and force the edges of the plates apart thus finding its way through. Now when a bullet strikes one of 50 these plates it will be deflected upward or downward and follow around the curve of the plate dropping backward onto the ground. Thus even if a bullet should find its way through the front of the shield it 55 would be stopped by the back.

In order to provide means whereby the soldiers may push the device forward, should it become desirable or necessary, grab irons 56 are fixed to the rear wall of the device 60 substantially on a line with the steering handle 26.

There has thus been provided a simple and efficient device of the kind described and for the purpose specified.

65 It is obvious that many minor changes

may be made in the form and construction of the invention without departing from the material principles thereof. It is not therefore desired to confine the invention to the exact form herein shown and described but it is wished to include all such as properly come within the scope claimed.

Having thus described the invention, what is claimed as new, is:—

1. The combination of a wheel supported shield; rotatable crushing means supported thereby and forwardly thereof; and means operatively connecting said crushing means and certain of the wheels supporting said shield to cause the rotation of said crushing 75 means.

2. The combination with a wheel supported shield; a frame carried by the front of said shield, a cylinder extending transversely of the shield and journaled in said frame, teeth projecting from said cylinder and means operatively connecting the cylinder and certain of the wheels supporting the shield to cause said cylinder to rotate in the direction of rotation of the supporting 85 wheels.

3. The combination with a wheel supported shield; a frame carried by the front of said shield, a cylinder extending transversely of the shield and journaled in said frame, teeth projecting from said cylinder, means operatively connecting the cylinder and certain of the wheels supporting the shield to cause said cylinder to rotate in the direction of rotation of the supporting 95 wheels, other cylinders above and to the rear of the first-mentioned cylinder and journaled in said frame, teeth on the last-mentioned cylinders and means operatively connecting the last-mentioned cylinders with the first cylinder and arranged to cause rotation of the last-mentioned cylinders in a direction opposite the first cylinder.

4. The combination with a wheel supported shield; a frame carried by the front of said shield, a cylinder extending transversely of the shield and journaled in said frame, teeth projecting from said cylinder, means operatively connecting the cylinder and certain of the wheels supporting the shield to cause said cylinder to rotate in the direction of rotation of the supporting 110 wheels, other cylinders above and to the rear of the first-mentioned cylinder and journaled in said frame, teeth on the last-mentioned cylinders and means operatively connecting the last-mentioned cylinders with the first cylinder and arranged to cause rotation of the last-mentioned cylinders in a direction opposite the first cylinder, and a 115 roof on said shield having an acuminate ridge curved upwardly from front to rear.

5. In a device of the kind described, a wheel supported shield including a front wall, a rear wall spaced from the front wall 120

and a series of bullet deflectors fixed to the forward face of the rear wall, said deflectors each consisting of a reversely curved plate, the lower edge of one plate being bent around the upper edge of the next plate below and the corrugations extending transversely of the shield.

In testimony whereof I affix my signature in the presence of two witnesses.

KARL KEMPNY.
